REFLECTING SIGN

William T. Levitt, Corning, N. Y., assignor to
Corning Glass Works, Corning, N. Y., a corpora-
tion of New York

Application December 26, 1933, Serial No. 704,036

3 Claims. (Cl. 40—130)

This invention relates to reflecting signs and more particularly to the mounting of reflecting units from which such signs can be made.

Reflecting signs of the type to which this in-

vention relates are generally made of metal stampings into which reflecting units commonly referred to in the art as reflex buttons are fitted. Such reflex buttons usually consist of a solid body of glass having at one end an objective lens and at its opposite end a concave reflector the reflecting surface of which coincides with the principal focus of the lens. Usually the reflector is of greater diameter than the lens so as to provide a relatively wide acceptance angle for the unit and hence the unit is frequently formed with a shoulder intermediate the objective lens and the reflector. In some instances however the sides of the unit taper from the reflector toward the lens so as to form a substantially cone-shaped body.

20 The primary object of my invention is to facilitate the production of reflecting signs employing reflecting units of the type above referred to.

Another object is to obtain uniformity of spacing between the reflecting units so that maximum visibility of the sign is obtained.

To this end my invention embodies in combination with a strip of flexible material having spaced openings, reflecting units which are secured in the openings so that the whole constitutes a unitary flexible member from which signs and sign characters or letters may be formed.

In the drawing:

Fig. 1 is a plan view of a flexible strip such as I use in supporting reflecting units in proper relation;

Fig. 2 is a side view of Fig. 1 partly in section;

Fig. 3 is a view similar to Fig. 2 showing reflecting units in place in the strip;

Fig. 4 is a fragmentary view of a sign embodying my invention;

Fig. 5 is a view illustrating a character produced by my invention; and

Fig. 6 is a side view partly in section of a modified form of my invention.

In carrying my invention into practice I employ a strip 10 of flexible material, preferably rubber, which is provided at spaced intervals with openings 11 each of which is counterbored from the rear to form a chamber 12 and shoulder 13. Extending from the outer face of the strip 10 toward the back thereof intermediate the openings 11 and chambers 12 are recesses 14 which open through the sides of the strip and form webs 15 which are pierced to form openings 16.

through which attaching devices such as nails 17 are driven.

Reflecting units 18, each of which in the preferred embodiment of my invention comprises a body of glass having an objective lens 19, a reflecting surface 20 and a shoulder 21 between the lens and reflecting surface, are fitted into the openings 11 as shown in Fig. 3 so that their shoulders 21 engage the shoulders 13 and prevent further movement of the reflecting units toward the front face of the strip 10, it being understood that movement of the units in the opposite direction with relation to the strip is resisted by the frictional contact of the sides of the units with the walls of the openings 11 and chambers 15.

In Fig. 6 I have illustrated my invention adapted for use in connection with reflecting units which taper from one end toward the other. In this form of my invention I provide a strip 22 of flexible material which is formed with spaced tapered openings 23 into which reflecting units 24 are fitted so that their smaller ends, or those forming the objective lenses of the units, project slightly beyond the plane of the front face of the strip. Like the strip 10, the strip 22 is provided between each pair of openings 23 with recesses 25 to form webs 26 which are apertured to receive attaching devices. Like the construction previously described, the reflecting units 24 are held in proper position by the frictional contact of their sides with the walls of the openings 23.

In use I prefer to assemble the reflecting units 18 into the strip 10 or 22 at the point of manufacture and then roll the strip in one continuous piece, cut it into convenient lengths for transportation. After the strips arrive at the point at which a sign is to be erected they may be cut into proper lengths to form the letters or characters desired as illustrated in Figs. 4 and 5. By reason of the flexibility of the strips it is obvious that such letters as S and O can be readily formed and many unique and intricate signs and shapes may be worked out. After the pieces have been cut to proper length they are fastened to an ordinary sign board 27 by means of suitable fastenings such as nails 17. Thus, complete signs may be made at very nominal expense as the use of metal stamping machinery and similar expensive operations is eliminated. Moreover, an individual or municipality may keep a supply of such sign-making material on hand and may use it as desired, such, for instance, as in temporarily rerouting traffic around highway construction and repairs.

While in the foregoing there has been shown and described the preferred embodiment of my invention, it is to be understood that minor changes in the details of construction, combination, and arrangements of parts may be resorted to without departing from the spirit and scope of my invention as claimed.

5 What I claim is:

1. A reflecting sign comprising a strip of flexible material having openings at spaced intervals in its outer face, said strip also having chambers opening from its rear side and communicating with the inner ends of the openings, shoulders formed at the junction of the openings and chambers, and shouldered reflecting units in the openings, the shoulders of the reflecting units engaging the shoulders formed at the junction of the openings and chambers.
- 10 2. A reflecting sign comprising a strip of flexible material having openings at spaced intervals in

its outer face, said strip also having chambers opening from its rear side and communicating with the inner ends of the openings, shoulders formed at the junction of the openings and chambers, shouldered reflecting units in the openings, webs on opposite sides of the strip, and attaching devices extending through the webs.

5

3. A reflecting sign comprising a strip of flexible material having openings at spaced intervals in its outer face, said strip also having chambers opening from its rear side and communicating with the inner ends of the openings, shoulders formed at the junction of the openings and chambers, shouldered reflecting units in the openings, the shoulders of the reflecting units engaging the shoulders formed at the junction of the openings and chambers, said strip having recesses in its sides between the openings to form webs, and attaching devices extending through the webs.
